UNITED STATES PATENT OFFICE

PETER E. BLONDIN, OF NORTH TONAWANDA, NEW YORK

STRINGED MUSICAL INSTRUMENT

Application filed August 19, 1931. Serial No. 558,003.

The principal object of my invention has been to provide a stringed musical instrument which combines the musical tones of a harp, a guitar, and a triangle.

5 Another object has been to provide a device having great resonance and tone carrying qualities.

Furthermore, my device not only combines the tone qualities of the harp, guitar, and triangle in a single instrument, but it may be played like a harp.

Moreover, my instrument has such tone qualities that only gut strings need be used to get all the resonance desired.

15 The above objects and advantages have been accomplished by the device shown in the accompanying drawings, of which:

Fig. 1 is a front elevation of my complete device.

20 Fig. 2 is a back view thereof.

Fig. 3 is a sectional plan view, taken on line 3—3 of Fig. 1.

Fig. 4 is a sectional view, taken on line 4—4 of Fig. 1.

25 Fig. 5 is a sectional view, taken on line 5—5 of Fig. 4.

Fig. 6 is an enlarged, sectional view, taken on line 6—6 of Fig. 3.

Fig. 7 is an enlarged, sectional view, taken 30 on line 7—7 of Fig. 1.

My device comprises in general a sound box 10 like that of a harp, a string-carrying member 11, like that of a guitar; and resonator irons 12 and 13 with metal rods, to be herein-after described, forming a structure producing the effect of a triangle.

The sound box 10 comprises a flat sounding board 15, which is preferably trapezoidal in shape with its larger width at the top of the instrument, as shown in Fig. 1. The back 16 of the sound box is oval-shaped, and is suitably joined to the sounding board 15, molding 17 being preferably provided around the edges of the sounding board. The sound box

45 is provided with a top 18, and a bottom 19 to which the sounding board 15 and back 16 are secured. A cap 20 is preferably arranged on top of the sound box and is secured to the upper face of the top 18. A shoe 21 is provided at the bottom of the sound box and is

secured to the bottom 19 thereof. This shoe forms a base for the instrument and is preferably provided with tapered sides for engagement with and support by a suitable standard. This shoe is relatively thick, and, therefore, aids in producing a rich, full tone by carrying the vibrations downwardly. The top 18 and cap 20 are of substantially the same contour as the top of the sound box, as shown by the cross-sectional view of Fig. 4. The bottom 19 and shoe 21 are of substantially the same contour as the bottom of the sound box, as shown by the sectional view of Fig. 3.

The back 16 is provided in its central portion with two sound openings 25 and 26 which are preferably of general trapezoidal contour having their wider dimensions at the top, as shown in Fig. 2, which adds materially to the tone value of the instrument. The sounding board 15 is stiffened and reinforced by a vertically arranged cleat 27 which is secured to the inside face thereof and extends for substantially the entire length of the board. At each side of this cleat and at substantially a point midway of the cleat and the outer edges 75 of the board is arranged an oblique cleat 28 which is preferably tapered at each end and having its upper end extending outwardly away from the central cleat. Extending preferably at right angles to these cleats are auxiliary cleats 29 which have one end abutting the oblique cleat 28 and the other end pointing inwardly toward the central cleat. Near the lower portion of the sounding board there are provided two cleats 30 which are 80 obliquely arranged and have their upper ends extending inwardly toward the central cleat. These cleats are so spaced as to be located substantially centrally of the distance between the central cleat and the edge of the board and aid in softening the tone and also act as tone carriers to the resonator irons 12 and 13. These cleats are shown largely in dotted lines in Fig. 2.

The triangle of my device is formed in part 95 by the resonator irons 12 and 13 which are preferably formed of flat material. Each of the irons is provided respectively with inner ends 35 and 36; outer ends 37 and 38, respectively, and connecting curve portions 39 and 100

40, respectively. The inner end 35 of the iron 12 is embedded in the top of the sounding box and preferably disposed between the top 18 and cap 20, where it is suitably secured. In like manner, the inner end 36 of the iron 13 is disposed at the bottom of the sound box and is securely embedded by being disposed preferably between the bottom 19 and shoe 21. The irons are so disposed that they project outwardly away from the face of the sounding board and at angle thereto as clearly shown. The inner ends 35 and 36 of these irons extend inwardly sufficiently far so that some portion thereof is disposed at the center of the top 18 and bottom 19. In the central portion of the top 18 is formed an opening 45, and in the bottom 19 is also formed a centrally arranged opening 46. These openings extend clear through the top and bottom and expose a portion of the inner ends 35 and 36 of the side irons 12 and 13, respectively, whereby the vibrations set up within the sound box will be communicated to the triangle of the instrument through the resonator irons. The outer ends 37 and 38 of the resonator irons 12 and 13, respectively, are interspaced and extend inwardly toward each other, and are secured to a triangularly shaped block 47. This block is solid and forms the suspension and opening of the triangle of the device, as well as forming the support for the string carrying member 11 of the device. The outer ends 37 and 38 may be secured to the flat faces of the block, or the instrument may be made more ornamental by setting these ends down below the surface of the block, as shown in Figs. 1 and 7, it being necessary, however, that the edges of the ends are free and separated from the wood surrounding them, so as not to interfere with the vibrations set up within the triangle. The string carrying member 11 is so positioned that its axis is preferably perpendicular to the longitudinal axis of the sound box and at an angle to the lateral axis of the sound box.

The other part of the triangle is formed by resonator rods 50, 51, 52, 53, 54 and 55 which correspond in number to the number of strings provided on the instrument and are preferably round in cross-section. Rods 50, 51, and 52 correspond to the bass strings, and rods 53, 54, and 55 correspond to the treble strings. All of these rods have their ends extending inwardly and are securely fastened to the top 18 and bottom 19 by being embedded or let in between the top 18 and cap 20 and between the bottom 19 and shoe 21. All of the rods have their vertical portions interspaced from the back 16 of the sound box 10. The inwardly projecting ends of the treble rods 53, 54, and 55 are not only embedded in the end of the sound box, but are securely fastened to the inwardly extending ends 35 and 36 of the resonator irons 12 and 13, respectively. As shown in Fig. 6,

the inwardly extending end of the rod 54, as illustrative also of rods 53 and 55, is joined to the inner end 36 of the resonator iron by being spliced, the joint being preferably secured by means of a screw 56. The three rods, therefore, which represent the treble tone are tightly joined to the resonator irons, whereas the three remaining rods 50, 51 and 52 representing the bass tone, requiring as they do, less vibration, are not joined to the resonator irons. From the foregoing it will be clearly seen that the resonator irons 12 and 13, together with the resonator rods 50, 51, 52, 53, 54, and 55 form the triangle part of my instrument.

As hereinbefore stated, the string carrying member 11 is preferably like the standard neck of a guitar, and has the finger-board 60 formed on the face thereof, as is customary. Secured to the central portion of the sounding board 15 is the bridge 61 of my instrument. This bridge is preferably made of soft wood having a piece of ebony or ivory 62, extending across the edge which faces the neck to act as a rest for the strings 63, of which there are preferably six in number. Pegs 64 of the type ordinarily used in a guitar or harp enter the bridge and serve to hold the ends of the strings 63 in place in a manner similar to that of a harp.

The instrument is played on the same principal as a harp, i. e., by picking the strings, and is suitable for orchestral, concert or home use. Obviously, it may be made in any suitable size. When the strings are played, the harp-shaped sound box 10 which is arranged at a proper angle, with the proper distance existing between the bridge 61 and the solid wooden block 47, produces the harp tone of the instrument. The instrument is played with great ease.

Obviously, some modifications of the details herein shown and described may be made without departing from the spirit of my invention or the scope of the appended claims, and I do not, therefore, wish to be limited to the exact embodiment herein shown and described, the form shown being merely a preferred embodiment thereof.

Having thus described my invention, what I claim is:

1. A stringed musical instrument comprising a sound box having a sounding board, a string carrying member in interspaced relation with the sound box, strings carried by the member and having their inner ends attached to the sounding board, said string carrying member having its axis arranged perpendicularly to the longitudinal axis of the sound box and at an angle to the lateral axis of the sound box, and resonator members connecting the string carrying member with the sound box.

2. A stringed musical instrument comprising a sound box, resonator members one end

of each of which being secured to opposite ends of the sound box, a block in interspaced relation with the sound box, the opposite ends of the resonator members being secured to and supported by the block, and a string carrying member secured to the block.

5 3. A stringed musical instrument comprising a sound box, a string carrying member in interspaced relation with the sound box, resonator irons connecting the string carrying member with each end of the sound box, and resonator rods connecting the opposite ends of the sound box.

10 4. A stringed musical instrument comprising a sound box, a string carrying member in interspaced relation with the sound box, resonator irons connecting the string carrying member with each end of the sound box and having their outer ends interspaced, and resonator rods connecting the opposite ends of the sound box, a number of said resonator rods having their opposite ends contacting with the resonator irons.

15 5. A stringed musical instrument comprising a sound box, a block in interspaced relation with the sound box, resonator members connecting the block with the sound box, the outer ends of the members which are secured to the block being interspaced, resonator rods connecting opposite ends of the box, a number of said rods having their opposite ends connected to the resonator members, and a string carrying member secured to the block.

20 6. A stringed musical instrument comprising a sound box, a string carrying member in interspaced relation with the sound box, and two oppositely arranged resonator members connected at opposite sides of one end only of the string carrying member and having their opposite ends connected one to each end of the sound box, said resonator members having their inner ends embedded in the ends of the sound box.

25 7. A stringed musical instrument comprising a sound box, a string carrying member in interspaced relation with the sound box, and resonator members connecting the string carrying member with the sound box, said resonator members having their inner ends embedded in the ends of the sound box, the ends of the box being each formed with an opening opposite the inner end of the resonator members, whereby the vibrations produced within the box will be communicated to the resonator members.

30 8. A stringed musical instrument comprising a sound box, a string carrying member in interspaced relation with the sound box, resonator irons connecting the string carrying member with each end of the sound box, said resonator irons having their inner ends embedded in the ends of the sound box, resonator rods arranged in interspaced relation with the sound box and having their ends embedded in opposite ends of the box, the

ends of the box being each formed with an opening opposite the inner end of the resonator irons, whereby the vibrations produced within the box will be communicated to the resonator irons.

35 9. A stringed musical instrument comprising a sound box having a sounding board, a string carrying member in interspaced relation with the sound box and having its axis arranged at an angle with the lateral axis of the sounding board, a bridge carried by the sounding board, and resonator members connecting the string carrying member with each end of the sound box.

40 10. A stringed musical instrument comprising a sound box of general tapered formation and formed with a curved back and flat sounding-board secured to the back, the top of the box being larger than the bottom thereof, a string carrying member in interspaced relation with the sound box, and resonator members connecting the string carrying member with the sound box.

45 11. A stringed musical instrument comprising a sound box of general tapered formation and formed with a curved back and flat sounding-board secured to the back, the top of the box being larger than the bottom thereof, the back of the sound box being formed with two sound openings, a string carrying member in interspaced relation with the sound box, and resonator members connecting the string carrying member with the sound box.

50 12. A stringed musical instrument comprising a sound box of general tapered formation and formed with a curved back and flat sounding-board secured to the back, the top of the box being larger than the bottom thereof, a centrally arranged cleat extending substantially the full length of the sounding-board and secured to the inner face thereof, and a plurality of short, narrow cleats also secured to the inside surface of the sounding-board and arranged in interspaced relation to the centrally arranged cleat and having their axes arranged at angles with the axis of the central cleat, a string carrying member in interspaced relation with the sound box, and resonator members connecting the string carrying member with the sound box.

55 13. A stringed musical instrument comprising a sound box of general tapered formation and formed with a curved back and flat sounding-board secured to the back, the top of the box being larger than the bottom thereof, a centrally arranged cleat extending substantially the full length of the sounding-board and secured to the inner face thereof, a pair of angularly arranged cleats secured near each end of the sounding-board, each pair having its members in interspaced relation with each other and with the central cleat, the axes of the members of each pair of

cleats converging inwardly toward the longitudinal center of the sounding-board, a string carrying member in interspaced relation with the sound box, and resonator members connecting the string carrying member with the sound box.

14. A stringed musical instrument comprising a sound box, a string carrying member in interspaced relation with the sound box, resonator irons connecting the string carrying member with each end of the sound box, resonator rods connecting the opposite ends of the sound box, a solid shoe arranged at the bottom of the box and fastened over the ends of the resonator members at the bottom of the box, and a cap arranged at the top of the box and fastened over the ends of the resonator members at the top of the box.

15. A stringed musical instrument comprising a sound box, a string carrying member in interspaced relation with the sound box and having its axis arranged at an angle with the lateral axis of the sounding-board, a bridge carried by the sounding-board, comprising a wooden body, a strip of relatively hard material arranged along one of the longitudinal edges of the body, and resonator members connecting the string carrying member with each end of the sound box.

16. A stringed musical instrument comprising a sound box, a string carrying member in interspaced relation with the sound box, two oppositely arranged resonator irons carried at opposite sides of one end only of the string carrying member and having their opposite ends connected one to each end of the sound box, and resonator rods connecting the opposite ends of the sound box.

17. A stringed musical instrument comprising a sound box, a block in interspaced relation with the sound box, resonator members connecting the block with the sound box, the outer ends of the members which are secured to the block being interspaced, resonator rods connecting opposite ends of the box, a number of said rods corresponding to the number of treble strings of the instrument being connected to the inner ends of the resonator irons, and a string carrying member secured to the block.

18. A stringed musical instrument comprising a sound box, two oppositely arranged resonator irons, one end of each of which being secured to opposite ends of the sound box, resonator rods carried by the sound box, a number of the rods being connected to the ends of the resonator irons, the opposite ends of the resonator irons being interspaced, whereby an open triangle construction is formed.

19. A stringed musical instrument comprising a sound box, two oppositely arranged resonator irons, one end of each of which being secured to opposite ends of the sound box, resonator rods carried by the sound box,

a number of the rods being connected to the ends of the resonator irons, a block in interspaced relation with the sound box, the opposite ends of the resonator irons being secured to the block in interspaced relation with each other, whereby an open triangle construction is formed.

20. A stringed musical instrument comprising a sound box, a string carrying member in interspaced relation with the sound box, resonator irons connecting the string carrying member with each end of the sound box, and resonator rods connecting the opposite ends of the sound box and equal in number to the number of strings carried by the instrument.

21. A stringed musical instrument comprising a sound box, resonator members one end of each of which being secured to opposite ends of the sound box, a solid block in interspaced relation with the sound box, the opposite ends of the resonator members being secured to and supported by the block, and a string carrying member secured to the block.

In testimony whereof, I have hereunto signed my name.

PETER E. BLONDIN.
